DESIGN FOR A DRAWING TABLE

Roy A. Carlson, Bay Village, Ohio

Application December 6, 1940, Serial No. 97,118

Term of patent 14 years

To all whom it may concern:

Be it known that I, Roy A. Carlson, a citizen of the United States, residing at Bay Village, in the county of Cuyahoga and State of Ohio, have invented a new, original, and ornamental Design for a Drawing Table, of which the following is a specification, reference being had to the accompanying drawing, forming part thereof.

Figure 1 is a front perspective view of a drawing table showing my new design;

Figure 2 is a rear perspective view of the drawing table; and

Figure 3 is a plan view thereof.

I claim:

The ornamental design for a drawing table, substantially as shown.

ROY A. CARLSON.
